UNITED STATES PATENT OFFICE.

PAUL FLEMMING COX, OF JACKSON, MICHIGAN, ASSIGNOR TO THE JACKSON PRINTING PRESS COMPANY, OF JACKSON, MICHIGAN, A CORPORATION OF MICHIGAN.

WEB-FEEDING DEVICE FOR PRINTING-PRESSES.

No. 884,900.

Specification of Letters Patent.

Patented April 14, 1908.

Application filed October 10, 1907. Serial No. 396,842.

To all whom it may concern:

Be it known that I, PAUL FLEMMING Cox, of Jackson, in the county of Jackson and State of Michigan, have invented certain new and useful Improvements in Web-Feeding Devices for Printing-Presses; and I hereby declare that the following is a full, clear, and exact description thereof, reference being had to the accompanying drawings, which form part of this specification.

This invention is an improvement in web feeding devices for printing presses, and it is designed to feed a web continuously but with irregular motion to a movable bed press.

The invention in particular is designed for use in connection with web printing presses of the type shown in my Patent No. 847,912, of March 19, 1907, and I have herein shown the web feeding devices in connection with such a press in the drawings, but I do not consider the invention restricted to use in a press of this kind as it may be utilized in various web feeding machines however, and particularly where it is desired to feed a web during printing thereof at a speed varying with and in conformity to the movement of the type bed during the printing operation.

In the accompanying drawings I have illustrated several mechanisms embodying the invention and illustrating its nature and purpose, and I will now describe the same more particularly with reference thereto, and refer to the claims for summaries of parts and combination of parts for which protection is desired.

In the drawing—Figure 1 is a diagrammatic sectional elevation of a web printing press of the type described in my aforesaid patent and with my improved web feeding devices applied thereto. Fig. 2 is an enlarged detail view of the web feeding and delivering devices shown in Fig. 1. Fig. 3 is a detail view showing a modification of the web feeding devices; and Fig. 4 is a detail view showing another modification of such devices.

As shown in Fig. 1, the press has two opposite type beds B B, which may be reciprocated simultaneously in opposite directions by means of pitman E, connected to hangers b on the beds and to crank gears G, hung on shafts g extending transversely through the press, said gears intermeshing so that they will be driven in opposite directions and

consequently the beds be reciprocated in opposite directions. The gears may be driven by a pinion h, mounted on a transverse driving shaft H, and meshing with one of the gears G, as shown. Above each type bed are two cylinders I, I', said cylinders may be mounted in eccentric boxes X, which are connected to longitudinal bars W, pivotally connected at one end to a lever V, which is connected by a rod U, to a lever T, pivoted at one end on a frame and carrying a roller t, engaging a race cam S, on one of the gears G, or attached to the shaft thereof, as shown, so that at the proper time the cylinders may be thrown on or off impression.

The course of the web is as follows: The web is led in from a roll J, at one end of the machine to and around a feed roll N', thence passes over a guide o, to and between the left-hand bed B and its cylinder I, up over guides o', o'', between the left-hand cylinder I' and bed B; thence back over guides o³, o⁴, down between right-hand cylinder I and its bed B, up over guides o⁵, o⁶, down between right-hand cylinder I' and bed B, then up over guides o⁷, to delivery roll P'. The feed and delivery rolls N', P', are irregular in outline and appear eccentric to their shafts or axes of rotation, but are caused to turn once for each reciprocation of the bed by means of a gear N³ on the shaft of roll N' meshing with a gear G³ of similar size on the shaft g, of one of the adjacent gears G. Any other suitable gearing may be employed to rotate the irregular feed roll in the proper time and relation to the movements of the beds.

As shown in Fig. 1, the delivery roll P' is of shape corresponding to that of the in-feed roll N'. In the press shown the rolls N', P', are designed to make one revolution for each sheet printed. The peripheries of these rolls have such an outline as to impart a movement to the web practically exactly uniform with the speed of the type beds B, during the actual printing operations, that is—when the cylinders I, I', are actually on impression, during the printing strokes of the beds. The rolls N', P', are also so shaped that while the beds are out of impression they will feed forward the desired amount of web into position to be printed at the next operation of the press.

It is obvious that during the printing

operation the web must be fed forward through the press in exact uniformity with the speed of movement of the beds and therefore a part of the periphery of each roll N' , P' , must be accurately shaped to so feed the web during the printing operations; and the remainder of the periphery of such roll is also so shaped as to feed the amount of web that it is desired to shift between the beds and 10 cylinders after impression. The peripheries of the rolls are shaped as desired according to the length of web to be fed—any sudden jerk or stoppage of the web at the beginning or end of the printing operation being prevented by merging the printing and non-printing feed portions of the rolls in a proper manner.

In the press shown the cylinders I , I' , print only on the outward strokes of the 20 beds, and while the web is moving onward from the feed to the delivery. And as described in my patent, the cylinders I , I' , in each pair, print different portions of the web, that is, the cylinders I , print alternate spaces 25 on the web, and the cylinders I' print the portions of the web skipped by the cylinders I . This enables me to shorten the strokes of the beds and to print say—thirty-five inches of paper by a seventeen and one-half inch 30 movement of the bed during printing,—as described in my said patent. Thus seventeen and one-half inches of web (less the margins) must be fed between the bed and cylinders during the actual printing operations, and seventeen and one-half inches of 35 web (plus the margins) be fed between the beds and cylinders while the impression is thrown off. I thus practically feed as much web during impression as is fed after impression, and the web is always moving forward 40 in the same direction.

By means of the irregular web feeding and delivering cylinders N' , P' , properly constructed, the web will be fed forward between the beds and cylinders during impressions at the speed desired and in exact accordance with the irregular crank movement of the bed; and after impressions the remaining length of web will be fed forward at substantially uniform speed, if desired. Thus 50 the web is continuously fed through the press and the feed and delivery rolls themselves compensate the web for the crank motion of the bed and I am able to dispense with any auxiliary or compensating looping rollers for the web.

The roll P' , may be driven from the roll N' by a suitable train of gears p , as shown in the drawings, so that the feed and delivery will 60 be in exact unison.

I preferably employ tapes Q and R , in connection with rolls N' , P' , the tapes Q passing over suitable guide rollers q^6 and N^2 . The roller N^2 may be located above and be a substantial duplicate of the roll N' and geared 65

to rotate therewith and set, so that the peripheries of the roll N' and roller N^2 will remain substantially equi-distant at their point of closest approximation, and hence the roller N^2 will keep the tapes Q at substantially uniform tension and compensate them for the irregularity of roll N' .

As a further means of maintaining uniform tension on the tapes, the roller q' can be mounted in swinging arms U , which are pivoted at u on the main frame, and rods u' are connected to arms U' and extend through lugs U^2 on the frame and have a washer and nuts U^3 on their upper ends, a spring U^4 being interposed between the washer and lug U^2 , so as to normally draw the roller q' away from roll N' , and thus keep the tapes Q under uniform tension and compensate same for the irregularity of the roll N' . The tapes R , co-acting with roll P' , may be guided over rollers r , r' ; and the roll p^2 may be constructed like roll P' if desired and serve the same purpose relative to the tapes R , that roller N^2 serves for tapes Q ; and if desired roller r' might be made adjustable for the same purpose as roller q' .

As shown in Fig. 3, the irregular roll N^2 can be dispensed with and an ordinary tape guide roller q^3 , used in place thereof, feed roll N' remaining the same. In this case roller q' is depended upon to take up the slack in the tapes occasioned by irregularity of roll N' . Instead of using a spring to control roller q' , it may be mounted in sliding bars Q' , which have pins Q^2 , engaging a race cam Q^3 on the end of roll N' , or secured to its shaft, and by which the roller q' will be moved in or out exactly as required to maintain the proper tension of the tapes against the irregular surface of roll N' , during rotation thereof. A similar arrangement can be used in connection with the delivery roll P' .

As shown in Fig. 4, instead of using an irregular delivery roll P' , a cylindric delivery roll P^x may be used, co-acting with delivery tapes R , and this roll P^x is driven by a train of gears p from the roll N' , but operates with uniform speed. In order to compensate such delivery roll for the irregular movement of the web through the press, I provide a movable compensating looper W , and after the web leaves guide roller o^7 it is carried up over rollers o^8 , then down under looping roller W , and up to delivery roll P^x . The roller W is mounted on bars w , which are operated by cams W' , which may be fast to the shaft of roll N^2 , and are so proportioned as to raise and lower roll W at proper times so as to give up its loop of web as demanded by the continuously running roll P^x , while the cylinders are on impression; and after impressions it will descend sufficiently to take up any oversupply of web fed in faster than the delivery roll requires. The delivery roll P^x may be peripherally speeded so as to deliver 130

the web continuously at a uniform speed both during and after impression. And the roller W is simply used to take care of the slightly irregular feed of the web required by 5 the movement of the bed.

The rolls N', P', N², P², might be described as epicycloidal rolls, as they are approximately oval in cross section, but as they are not absolutely true epicycloids, I prefer to 10 term them in the description and claims "irregular"—meaning thereby that the said rolls are not truly cylindric or concentric to their axes of rotation, the rolls as a whole being eccentric to their axes of rotation.

Having described my invention what I 15 claim as new and desire to secure by Letters Patent is:

1. In a printing press, the combination of a printing couple operating at variable speed 20 during the printing, web guiding means, and an irregular feed roll adapted to feed a web at varying speed during its rotation; with a web delivery mechanism adapted to deliver the web fed by the feed roll, and to maintain 25 the tension of the intermediate portion of the web.

2. In a printing press, an impression couple operating at variable speed during the printing, web guides, a web feed roll of 30 irregular outline adapted to feed the web forward at variable speed during its rotation as required by the impression couple, a delivery roll adapted to deliver the web, and gearing between the feed and delivery rolls.

3. In a printing press, the combination of printing mechanism operating at variable speed during the printing, web guides and a web feed roll of irregular outline adapted to feed the web forward at variable speed during 40 its rotation as required by the printing mechanism; with means for rotating the feed roll, a delivery roll adapted to deliver the web fed in by the feed roll, and gearing between the feed and delivery rolls.

4. In a printing press, the combination of a printing couple and web guides, a feed roll having an irregular outline, tapes co-acting with said roll, means for automatically maintaining the tension of said tapes, and means 50 for rotating the roll, said feed roll being eccentric to its axis of rotation whereby the web is fed forward at irregular speed during the rotation of the roll; with a delivery roll adapted to deliver the web as fast as fed in by the feed roll, and gearing between the feed and delivery rolls.

5. In a printing press, the combination of a reciprocating type bed, a cylinder, and means for directing a web between the bed 60 and cylinder, and an irregular feed roll adapted to feed the web forward during impression at a speed conformable to the movement of the bed.

6. In a printing press, the combination of 65 a reciprocating type bed, a cylinder, and

means for directing a web between the bed and cylinder, and an irregular feed roll having an irregular outline and adapted to feed the web forward during impression at variable speed conformable to the movement of 70 the bed.

7. In a printing press, the combination of a reciprocating type bed, a cylinder, and means for directing a web between the bed and cylinder, and an irregular feed roll adapted to feed the web forward during impressions at a speed conformable to the movement of the bed, and to feed a like portion of the web forward during the return stroke of the bed and while the impression is thrown off. 75

8. In a printing press, the combination of a reciprocating type bed, a cylinder, and means for directing a web between the bed and cylinder, and an irregular feed roll having an irregular outline and adapted to feed the web forward during impression at variable speed conformable to the movement of the bed, and to feed a like portion of the web forward during the return stroke of the bed 80 and while the impression is thrown off. 85

9. In a printing press, the combination of a reciprocating bed, a cylinder co-acting therewith, and guides for directing a web between the bed and cylinder; a web feed roll 95 having an irregular outline, and means for continuously rotating this roll whereby the web is fed forward during impressions at the speed of travel of the bed and also fed forward after impressions. 100

10. In a printing press, the combination of a reciprocating bed, a cylinder co-acting therewith, guides for directing a web between the bed and cylinder, a feeding mechanism comprising a web feed roll mounted eccentric to its axis of rotation, means for rotating this roll whereby the web is fed forward during impressions at the speed of travel of the bed and also fed after impression at a uniform speed; with a delivery 105 mechanism adapted to draw the web through the press at a speed uniform with its feed. 110

11. In a printing press, the combination of a reciprocating bed, a cylinder co-acting therewith, means for directing a web between the bed and cylinder, a web feeding roll mounted eccentric to its axis, tapes co-acting with said roll and means for maintaining the tension of said tapes whereby the web is fed to the press during impression at a speed 115 uniform with the movement of the bed. 122

12. In a printing press, the combination of a reciprocating bed, a cylinder co-acting therewith, means for directing a web between the bed and cylinder, a web feeding roll 125 mounted eccentric to its axis, tapes co-acting with said roll whereby the web is fed to the press during impression at a speed uniform with the movement of the bed; and a web delivery mechanism comprising a roll and 130

tapes co-acting therewith adapted to draw the web through the press at a speed coincident with its feed thereto.

13. In a printing press, the combination of 5 a reciprocating bed, a cylinder co-acting therewith, means for directing a web between the bed and cylinder, a web feeding roll mounted eccentric to its axis, tapes co-acting with said roll and means for maintaining the 10 tension of said tapes whereby the web is fed to the press during impression at a speed uniform with the movement of the bed; and a web delivery mechanism comprising a roll of irregular outline and tapes co-acting there- 15 with adapted to draw the web through the press at a speed coincident with its feed thereto, and gearing between the feed and delivery mechanisms.

14. In a printing press, the combination of 20 a reciprocating bed, a pair of cylinders co-acting therewith, means for directing a web successively between the cylinders and the bed, and a feed roll mounted eccentric to its axis of rotation adapted to feed the web be- 25 tween the bed and cylinders during impres- sion at a speed uniform with that of the bed movement.

15. In a printing press, the combination of 30 a reciprocating bed, a pair of cylinders co-acting therewith, means for directing a web successively between the cylinders and the bed, and a feed roll of irregular outline adapted to feed the web between the bed and cylinders during impression at a speed uniform 35 with that of the bed movement and to feed a like length of web between the bed and cylinders after impression.

16. In a printing press, the combination of 40 a reciprocating bed, a pair of cylinders co-acting therewith, means for directing a web successively between the cylinders and the bed, and a feed roll mounted eccentric to its axis of rotation adapted to feed the web be- 45 tween the bed and cylinders during impres- sion at a speed uniform with that of the bed movement; with a web delivery roll of irregular outline adapted to draw the web through the press at a speed coincident with its feed.

17. In a printing press, the combination of 50 a reciprocating bed, a pair of cylinders co-acting therewith, means for directing a web successively between the cylinders and the bed, and a feed roll of irregular outline adapted to feed the web between the bed and cylinders during impression at a speed uniform 55 with that of the bed movement and to feed a like length of web between the bed and cylinders after impression; with a web delivery roll of irregular outline adapted to draw the 60 web through the press at a speed coincident with its feed.

18. In a web perfecting printing press, the

combination of reciprocating type beds and co-acting cylinders, guides for directing a web between the cylinders and beds, a feed 65 roll of irregular outline adapted to feed the web through the press at a speed uniform with the movement of the beds during im- pression, and a delivery mechanism adapted to draw the web through the press at a speed 70 coincident with its feed.

19. In a web perfecting printing press, the combination of reciprocating type beds, a pair of cylinders co-acting with each of said beds, guides for directing a web successively 75 between the cylinders and beds, a feed roll of irregular outline adapted to feed the web through the press at a speed uniform with the movement of the bed during impression and to feed a similar length of web to the 80 press after impression, and a delivery mech- anism adapted to draw the web through the press at a speed coincident with its feed.

20. In a web printing press, the combina- 85 tion of a pair of reciprocating beds and co- acting cylinders, a web feeding roll of irregu- lar outline, tapes co-acting with said roll, means for rotating said roll at uniform speed whereby a length of web is fed to the press during impression at a speed uniform with 90 the movement of the beds and a like length of web is fed to the press while the impres- sion is thrown off, a web delivery mechanism adapted to draw the web through the press at a speed coincident with its feed, and guides 95 for directing the web from the feed roll suc- cessively between the cylinders and beds and thence to the delivery.

21. In a web printing press, the combina- 100 tion of a pair of oppositely reciprocating beds, a pair of cylinders co-acting with each bed, a web feeding mechanism comprising a roll of irregular outline, tapes co-acting with said roll, means for tensioning the tapes, and means for rotating said roll at uniform speed 105 whereby a length of web is fed to the press during impression at a speed uniform with the movement of the beds and a like length of web is fed to the press while the impres- sion is thrown off; with a web delivery mech- anism adapted to draw the web through the 110 press at a speed coincident with its feed, and guides for directing the web from the feed roll and between one pair of cylinders and bed and then to and between the next pair of 115 cylinders and bed, and thence to the delivery mechanism.

In testimony that I claim the foregoing as my own, I affix my signature in presence of two witnesses.

PAUL FLEMMING COX.
